ENGINE STARTER

Raymond P. Lansing, Montclair, N. J., assignor to
 Eclipse Machine Company, Elmira Heights,
 N. Y., a corporation of New York

Original application January 8, 1929, Serial No.
 331,093. Divided and this application August
 24, 1934, Serial No. 741,309

4 Claims. (Cl. 123—179)

This invention relates to engine starters and more particularly to a starter of the inertia type.

Although the particular inventive embodiment illustrated in the accompanying drawing differs 5 patentably from the inventive embodiment disclosed in my co-pending application No. 331,093, filed January 8, 1929, certain of the claims of this application are directed to the invention generically considered, and therefore dominate 10 the species disclosed and claimed in the said earlier filed application. The embodiment of the invention herein illustrated was originally shown in the said earlier filed application but is not claimed therein either generically or specifically.

One of the objects of the present invention is to provide a novel engine starter of the inertia or flywheel type, a motor for rotating the flywheel, the motor having the longitudinal axis 20 thereof disposed substantially parallel to the axis of rotation of the flywheel and laterally spaced therefrom, whereby the length of the structure is materially reduced without excessive increase in the transverse dimensions thereof.

A further object is to provide novel starting mechanism of the above character which embodies manually operable means for rotating the flywheel, said manually operable means being adapted for actuation independently of the motor or for conjoint action, and being angularly 30 adjustable in relation to the power means.

In the accompanying drawing which constitutes a longitudinal view in section of the preferred embodiment of the invention, a flywheel 5 is shown as adapted to rotate an engine engaging member or clutch jaw 6 which is movable into driving engagement with a jaw member 7 connecting with or constituting part of the engine crankshaft. The starting apparatus also includes a housing constituted by inner sections 8, 82, and 82^a, and an outer section 80 within which is rotatably mounted the flywheel 5, said housing sections being connected by suitable means 81. The flywheel 5 is rotatably mounted 40 as by means of suitable bearings 83 in a wall or diaphragm 84 which is clamped between housing sections 80 and 82. In this preferred embodiment of the invention, the flywheel is keyed to a shaft 16 having an opening therethrough. Extending freely through the opening in shaft 16^a is a shaft 85 which is rigidly connected in any suitable manner at its inner end to the closed end of barrel 81^a. The outer end of shaft 85, which is hollow, has drivably connected thereto a bevel gear 86 which is rotatably supported as by

means of a bearing 87 in the end wall of housing section 80. Secured to the outer end of said section 80 by means of screws is a casing 88 in which is rotatably mounted a cranking shaft 89. The inner end of said shaft carries a bevel gear 90 which meshes with the bevel gear 86, and the outer end of said shaft is adapted to be engaged by a suitable hand crank, not shown.

By adjusting the position of casing 88 relative to housing section 80 the angular position of 10 cranking shaft 89 may be varied as desired to facilitate engagement of the hand crank with said cranking shaft, and this without interrupting the driving connection between gears 86 and 90. Extending freely through shaft 85 15 and jaw member 6 is a rod 69 which terminates adjacent its outer end within the casing 88, and has a pin and slot connection with a lever arm 91 that is rigidly connected to a rockshaft 92 carrying the bell crank 74 by which said rod 69 20 may be moved longitudinally to move jaw member 6 into driving engagement with jaw member 7.

In order to reduce the overall length of the apparatus and at the same time provide a compact, 25 symmetrical arrangement, the motor 57, which is preferably of an electric character, has its longitudinal axis laterally spaced from and disposed substantially parallel to the axis of rotation of the flywheel, with the inner end of said 30 motor extending inwardly beyond the vertical plane of the flywheel 5. One end of the armature shaft 60 of the motor projects into the casing section 82^a, and is threaded for a portion of its length to receive a clutch member 61 adapted 35 for rotary and longitudinal movement relative to the shaft. The extremity of shaft 60 is preferably of reduced diameter and is threaded to receive a nut 62 which constitutes a retainer for a coil spring 63 that is interposed between said nut 40 and member 61 to normally hold the latter in non-driving position.

A stub shaft 64 is rotatably mounted by means of suitable bearings 65 in a boss 58^a provided in the wall of casing portion 82^a, said stub shaft being substantially coaxial with armature shaft 60. The end of shaft 64 adjacent clutch member 61 has rigidly connected thereto a bell shaped member 66 within which is secured a clutch member 67 adapted to be engaged and driven by clutch member 61. The periphery of the large end of member 66 is formed as a spur gear 68 meshing with a gear 94 which in turn meshes with the flywheel pinion 20 and is integral with a pinion 93.

The means for connecting the pinion 93 to the 55

5 clutch 6 preferably includes a gear 27 formed integrally with a pinion 28 that is rotatably mounted by means of a bushing 29 on a stub shaft 30 which is formed integrally with, and projects centrally from the closed end of a barrel 31^a rotatably mounted in inner housing section 8 by means of ball bearings 32.

10 Pinion 28 constitutes a sun gear for a plurality of planetary gears 33, one of which is shown in section in the drawing. Preferably three planetary gears are employed, the same being spaced at intervals of 120 degrees about the closed end of barrel 31^a, and said gears mesh with an internal gear 33^a which is secured in the manner shown 15 to the inner surface of housing section 8. Each planetary gear is rotatably mounted by means of a ball bearing 34 on a sleeve 35 having the inner end thereof countersunk in the outer face of the closed end of the barrel. A screw 36 extends 20 through the sleeve and is threaded into the end of said barrel. A retaining ring 37 is carried by the outer ends of the screws 36 and constitutes a retaining member for the ball bearings 34 and sleeves 35.

25 Means are preferably interposed between the gear train described above and the engine engaging member 6 for yieldingly transmitting the energy in the flywheel to the engine crankshaft without damage such as might result if the driving connections were entirely constituted by rigidly connected elements. For this purpose a multiple disc clutch is preferably employed, said clutch being mounted in barrel 31^a.

30 As shown, the clutch comprises a plurality of 35 annular discs 37^a, certain of the discs being splined at their outer peripheries to the inner surface of barrel 31^a, and the remaining discs being splined at their inner peripheries to the outer surface of an interiorly threaded nut 38 which is provided intermediate its ends with a flange 39. The 40 clutch discs are positioned between flange 39 and the closed end of barrel 31^a and adjustable yielding means are provided for holding nut 38 in operative position with respect to the discs and 45 barrel and for varying the frictional engagement of said discs.

50 In the illustrated embodiment the yielding means comprise a plurality of coil springs 40 which extend longitudinally within the barrel, 55 the outer ends of said springs having operative engagement with the flange 39. A ring 41 provided with a plurality of laterally projecting studs 42 is mounted in the barrel, with the studs extending into the coils of the springs whereby the latter are maintained in proper spaced relation. An adjusting nut 43 is threaded into the open end of the barrel and has abutting engagement with the inner face of ring 41. By adjusting the position of nut 43 longitudinally of barrel 31^a 60 the compression of springs 40 may be changed to vary the pressure with which the clutch discs or plates 37^a are engaged.

65 Externally threaded onto the inner end of barrel 31^a is a retaining ring 44 for the adjacent ball bearing 32. Ring 44 may be locked in position by means of a wire 45, and said ring is adapted to coast with a shoulder 46, provided on the outer end of the barrel and having engagement with the inner race of outer ball bearing 32, to 70 prevent endwise movement of the barrel relative to the inner housing section 8.

75 Positioned within nut 38 is a threaded shaft 47 adapted for rotary and longitudinal movement relative to the nut. The outer end of said shaft 78 is provided with suitable means such as a nut 48

adapted to engage a shoulder formed interiorly of member 38 to limit longitudinal movement of the shaft to the left as viewed in the drawing. The inner end of shaft 47 is longitudinally splined and extends into the correspondingly splined hub 5 portion of clutch member 6 whereby these parts have positive driving engagement, but are adapted for relative longitudinal movement. A coil spring 49, which preferably has its outer end extending into a recess in shaft 47, is interposed between 10 said shaft and the jaw member 6 and yieldingly resists movement of the jaw member toward the shaft.

15 Means are preferably provided for preventing oil from seeping from the cranking case into the 15 starter housing, since such oil would impair the operation of the apparatus. For this purpose a cup shaped member 75, which is preferably formed of metal and is provided on its outer end with a flange 75^a adapted to be clamped between flange 20 11 of the starter housing and the crank case 12 of the engine, is fitted over the inner end of the starter that projects into the crank case. Secured to the member 75 is a flexible guard or disc 76 of 25 annular form, the inner periphery of said guard 25 having engagement with the outer surface of the laterally projecting hub portion of jaw member 6. A sleeve 77 surrounds and has sliding engagement with the said hub portion and extends outwardly into abutting engagement with flange 39. 30 The inner end of sleeve 77 bears against a ring 78 to hold the latter in engagement with the flexible guard 76. The length of sleeve 77 is preferably such that the inner portion of guard 76 is flexed outwardly into engagement with the adjacent face of the jaw member 6 and seepage of oil 35 into the starter housing at this point is thereby prevented without interference with the longitudinal movement of the jaw member. A pair of washers 79, one of which may be formed of 40 flexible material, is mounted on rod 69^a intermediate shaft 41 and jaw member 6 to prevent seepage of oil through the central opening in said jaw member.

45 When it is desired to store energy in the flywheel, preparatory to cranking the engine, the operator engages a hand crank with the outer end of shaft 89 and rotates the latter. This motion is transmitted through the gear train to flywheel 5 whereby the latter is rotated a large number of times for each revolution of shaft 89. Actuation of shaft 89 results in rotation of barrel 31^a and all the parts therein with the exception of rod 68 which maintains jaw member 6 out of driving engagement with member 7. Stub shaft 55 50 64 and bell shaped member 66 are also rotated but no driving connection to motor 57 is established at this time.

55 After the flywheel has been brought to the desired speed of rotation, i. e., after sufficient energy 60 for cranking the engine has been stored therein, the operator actuates the bell crank lever 74, as by exerting a pull on a suitable cable connected to said lever, whereupon rod 69 is forced to the left as viewed in drawing. Shoulder 71 forces 65 shaft 47 to the left, the latter having a combined rotary and longitudinal movement due to its threaded connection with the nut 38, and jaw member 6 is yieldingly moved through spring 48 into full meshing engagement with jaw member 7. 70 The energy of the flywheel is now effective to crank the engine.

75 When the engine starts under its own power the speed of rotation of clutch member 7 is greater than that of jaw member 6, and the inclined teeth 75

of said jaw members are now effective to move member 6 to the right out of driving engagement. The yielding means associated with the rockshaft 92 is effective to move rod 68 to normal position when the operator releases bell crank lever 74.

If it is desired to employ motor 57 for energizing flywheel 5, the circuit to said motor is closed whereupon armature shaft 60 is rotated. The member 61 will now be automatically advanced 10 against the tension of spring 63, into driving engagement with the clutch member 67. A driving connection is now established between the motor and flywheel through gear 68, gear 94, and pinion 20 whereby the flywheel is rotated and energy is stored therein. The electric motor may be employed in conjunction with the crankshaft 89 to energize the flywheel as, for example, when it is desired to conserve the electrical energy employed for actuating the motor, or when the supply of electrical energy is low.

There is thus provided a novel engine starter of the flywheel type which is so constructed as to embody both motor and power means for energizing the flywheel, the structure being light in weight and symmetrical in form. By mounting the motor on the housing with the longitudinal axis of the armature shaft substantially parallel to the axis of rotation of the flywheel the overall dimensions of the starter are reduced, and a better distribution of weight is attained.

What I claim is:

1. In an engine starter of the type embodying a high speed flywheel, a housing having a laterally projecting portion, a shaft rotatably mounted in said projecting portion, a motor secured to the projecting portion of the housing, means for drivably connecting the motor and shaft, and means for drivably connecting the flywheel with said shaft, said last named means including a set of

gears all of which are disposed in a common plane parallel to and closely adjacent the end surfaces of both the motor and flywheel.

2. In combination with a member to be driven, a flywheel and a shaft operable to energize said flywheel, a pair of clutch elements movable longitudinally along parallel axes, one of which axes coincides with the axis of said shaft, means responsive to rotation of said shaft to cause longitudinal movement of one of said clutch elements 10 into position to transmit energy to said flywheel, and means movable axially of and within the flywheel to cause longitudinal movement of the other clutch element into position to drivably connect the flywheel with said member to be driven.

3. In combination with a flywheel and a shaft operable to energize said flywheel, a pair of clutch elements movable longitudinally along parallel axes, one of which axes coincides with the axis of said shaft, means responsive to rotation of said 20 shaft to cause longitudinal movement of one of said clutch elements, and means movable axially of and within the flywheel to cause longitudinal movement of the other clutch element, said last-named means including a second shaft and a rod 25 projecting from said second shaft at both ends thereof, and means located on opposite sides of said flywheel for supporting said shaft and rod.

4. In an engine starter, the combination with a high speed flywheel, a housing having a projecting portion, and a motor secured to the projecting portion of the housing, of means for drivably connecting the motor and flywheel, said means including a set of gears and clutch elements all of which are disposed in a common plane parallel to 30 and closely adjacent the end surfaces of both the motor and flywheel.

RAYMOND P. LANSING.
